UNITED STATES PATENT OFFICE.

JOHN McMULLEN, OF BUFFALO, NEW YORK.

DOOR OPENING AND CLOSING MECHANISM.

Application filed July 2, 1925. Serial No. 41,230.

This invention relates to a door opening and closing mechanism.

It is among the objects of this invention to provide a simple mechanism associated with

5 a car door for opening and closing the same and which serves to lock the door in any desired position.

10 The invention comprises the novel structure and combinations hereinafter described and more particularly pointed out and defined in the appended claims.

15 In the accompanying drawings, which illustrate a preferred embodiment of this invention and in which similar reference numerals refer to similar features in the different views:

Figure 1 is a fragmentary side elevational view of a box car to which my invention is applied,

20 Figure 2 is an enlarged sectional view upon the line II—II of Figure 1, and

Figure 3 is an enlarged sectional view taken upon the line III—III of Figure 1 with the lever in operating position.

25 In referring to the drawings, there is shown the side wall of a box car having a door 1 suspended from the usual rail 2 by means of the usual roller hangers 3.

Upon the rear edge of the door, there is a 30 pivot stud 4. A door opening and closing lever 5 is slidably pivoted intermediate its ends upon said stud by means of a slot 6 through which the shank of the stud extends. The stud has a head overlapping the slot for 35 retaining the lever against removal. One end of the lever 5 is provided with a handle portion 5^a, while the other end is restricted for engaging apertures 7 in the web of a channel member 8, attached to the side of the 40 car. This channel member may be termed a rack bar.

The lever 5 is provided with a laterally extending locking prong 9 adapted for engaging in a suitable aperture in the bottom flange of the channel 8 when the door is in closed position, as shown in Figure 2. The lever is adapted to be swung to a position above the stud 4, as illustrated in Figure 2, and in order to retain the lever in such position, it is provided with a stud 10 which is 45 designed to engage in a recess 11 formed in the upper edge of a metal keeper 12. This metal keeper is formed upon an angle plate 13 attached to the rear portion of the door, one 50 flange engaging the front face of the door and

the other flange engaging the rear edge of the door, the latter flange having an upper returned bent portion forming the keeper, as shown in Figure 1.

The lever is also provided with an apertured lug 14 adapted to engage between the apertured arms 15 of a lug 16 attached to the rear edge of the door. The arms 15 are spaced from the rear edge of the door so that the lever can be swung thereunder. A bolt 65 17 attached to a chain 18 may be inserted through the apertures in the arms 15 and lug 14 for locking the lever in pendant position.

In referring to Figure 3, it will be noted that the lever is cut away at the rear, as indicated at 19, for clearance so that the lever can be oscillated transversely to the door when swung at right angles thereto.

In the use of this invention, assuming that the door is closed, the lever is unlocked and 75 swung at right angles to the door and the inner end is engaged with the rack bar. The lever is then oscillated backwards and forwards engaging a different notch each time until the door is partially opened, or until it 80 can be manually operated. The lever may then be swung upwardly under the keeper 12 with the stud 10 engaging the recess 11.

The lever may also be utilized for forcing the door to a tight close by swinging the lever 85 again at right angles to the door, engaging the inner end with the rock bar and forcing the same against the rear of the door. When the door has been shifted as far as one movement of the lever permits, and the door is 90 not closed, the lever may be removed from the notch it is in engagement with and engaged with a more advanced notch so that the operation may be completed, and so on.

I am aware that many changes may be 95 made, and numerous details of construction may be varied through a wide range without departing from the principles of this invention, and I therefore do not purpose limiting the patent granted hereon, otherwise than 100 necessitated by the prior art.

I claim as my invention:

1. The combination with a sliding door, of a rack bar adjacent the rear of the door opening, a lever slidably pivoted upon the 105 rear edge of said door and swingable at right angles thereto for engaging with said rack bar, said lever having a locking prong adapted for engagement with said rack bar, and means for locking said lever to said door 110

- with said prong in locking engagement with said rack bar.
2. The combination with a sliding door, of an opening and closing lever slidably pivoted to the rear of said door and having a stud, a keeper having a recess and secured above the pivoted point of said lever, said lever being swingable under said keeper with the stud engageable in said recess.
- 10 3. The combination with a sliding door, of an opening and closing lever pivotally mounted to the rear end of said door, a rack bar mounted adjacent said door for engagement by said lever, said rack bar having a notch and said lever having a prong for engagement with said notch when said lever is positioned against the rear edge of said door when the same is in closed position.
- 20 4. The combination with a sliding door, of a rack bar adjacent said door comprising a channel member having apertures in its web and a locking aperture in one flange, a lever slidably pivoted to the rear of said door for co-action with said rack and adapted for engagement with said locking aperture when said door is in closed position.
- 25 5. The combination with a sliding door, of an opening and closing lever slidably pivoted to the rear edge of the door, a rack upon the car with which said lever is adapted to cooperate for moving said door, said rack having
- a locking aperture for receiving a portion of said lever when the same is in pendant position for locking said door.
- 35 6. The combination with a sliding door, of an opening and closing lever slidably pivoted to the rear edge of the door, means adjacent the rear of the door for engagement by said lever for operating said door, and a keeper above the pivot point of said lever for maintaining said lever in inverted position.
- 40 7. The combination with a sliding door, of an opening and closing lever slidably pivoted to the rear edge of the door, means at the rear of said door for engagement by said lever for operating said door, said means and lever being adapted for interlocking engagement when said door is closed, and means for locking said lever in such interlocking engagement.
- 45 8. The combination with a sliding door, of an operating lever pivoted to the rear of said door, means for engagement by said lever for moving said door, said lever having a prong for interlocking engagement with said means when said door is in closed position, said lever being swingable out of such interlocking engagement, and means for locking the same out of such interlocking engagement.
- 50 In testimony whereof I have hereunto subscribed my name.

JOHN McMULLEN.
